GLASS ROLLING APPARATUS

John H. Fox and William Owen, Pittsburgh, Pa.,
assignors to Pittsburgh Plate Glass Company, a
corporation of Pennsylvania

Application May 6, 1932. Serial No. 609,572

6 Claims. (Cl. 257—95)

The invention relates to glass rolling apparatus of the general type shown in the Gelstsharp Patent No. 1,615,834, dated February 1, 1927, wherein a sheet of glass is rolled vertically from a molten bath by a pair of sizing rolls which engage the surface of the glass, such glass sheet after formation being directed horizontally through an annealing leir. The invention has for its principal objects the provision of a simplified and improved structure at the ends of the rolls for supporting them and for supplying a cooling medium to the roll bearings and to the interior of the roll. A further object is the provision of a structure whereby the roll bearings may be placed relatively close to the drawing pot or receptacle, and whereby the length of the roll spindles may be reduced to a minimum. Certain embodiments of the invention are illustrated in the accompanying drawings, wherein:

20 Figure 1 is a vertical section through one form of apparatus. Fig. 2 is a vertical section through a modification. And Fig. 3 is a vertical section through still another modification.

Referring to Fig. 1, 1 is the draw pot or receptacle containing a body of molten glass 2, such pot being connected to a suitable melting tank, not shown; 3 is one of a pair of sizing rolls mounted so that its periphery engages the glass and consisting of a body portion 4 and a pair of spindles 5 at the end of the body portion, only one of which is shown. It will be understood that the half of the apparatus which is not shown is similar to that shown in Fig. 1 except that no driving means is applied to the other end of the roll. The driving means in this case comprises the tumbler shaft 5^a which engages the head 6 of the tumbler member which is secured to the end of the spindle. This tumbler member comprises a keyed end 7 which fits into the end of the spindle and is secured in position by means of the bolts 7^a, this being a drive means for rolls well-known in the art. Mounted in the spindle and roll is a tube 8 which divides the interior into a pair of concentric passages 9 and 10. The inner end of the pipe is connected to a similar pipe 8^a lying in the other half of the roll, the two ends being connected by the casting 11 provided with the perforations 12, 12 permitting a flow of liquid from the passageway 9 to the passageway 10. The outer end of the tube is mounted in a cylindrical casting 13 provided around its periphery with a groove 14 which communicates with the interior of the casting by means of the perforations 15. Packing is pro-

vided in a groove 16 around the periphery of the casting.

The roll spindle is supported in an arm 17 which has at its lower end integral therewith the sleeve 18. Mounted at the inner end of this sleeve is 60 a bearing member 19 provided with a spiral groove 20. This serves as a cooling passage, water being supplied to one end of the groove by the pipe 21 withdrawn from the other end by the pipe 22. This prevents the bearing from becoming over- 65 heated due to its proximity to the body of glass in the pot. Also mounted in the sleeve 18 are a pair of rings 23 and 24 provided with grooves around their peripheries and with perforations which register with perforations 25 and 26 70 through the spindle. Suitable packing is interposed between the bearing member 19 and the ring 23 and between the ring 23 and ring 24. Packing is also provided to the right of the ring 24, such packing being held in place by means 75 of the gland 27. Water is supplied for cooling the roll through a pipe 28 and withdrawn through the pipe 29. The inflowing water through the pipe 28 passes through the perforations 26 to the interior of the casting 13 and then flows to the 80 left through the pipe 8 and discharges into the passageway 10 through the openings 12. The water which is thus supplied to the middle of the roll flows to the right through the passageway 10 and discharges through the openings 25 to the 85 ring 23 and thence through the pipe 29. Provision is thus made in the sleeve 18 for cooling the bearing 19 and for circulating and cooling the flow of liquid back and forth through the roll. This makes a compact structure permitting of the 90 use of a relatively short spindle.

Fig. 2 illustrates a modification which differs from that of Fig. 1 in that the supply of cooling water is caused to flow first through the roll and then through the bearing so that the single flow 95 of water accomplishes the two functions, thus simplifying the construction as compared to that of Fig. 1 in which two sets of connections are required one for cooling the roll and the other for cooling the bearing. This is accomplished 100 by placing the passage through the bearing in series with the passageways through the roll and spindle. The construction of the roll and spindle in this form of apparatus is the same as in the Fig. 1 construction and requires no further 105 explanation. Two rings 30 and 31 are carried by the spindle and provided with suitable grooves and passages registering with the passages 25 and 26. Packing 32 is provided between the rings and also between the ring 30 and the bearing 33. 110

The bearing 33 is provided with a spiral groove 34 which is connected at its right hand end with the annular recess 35 around the periphery of the ring 30. Water admitted through the inlet pipe 36 flows through the ring 31 and passage 26 to the interior of the casting 13 and thence to the left through the pipe 8 as heretofore described in connection with Fig. 1. The return flow through the passageway 10 discharges through the openings 25 to the annular recess 35 and then flows through the spiral passage 34 to the outlet pipe 37. In this manner the cooling water is caused to first cool the roll and then the bearing.

Fig. 3 illustrates a further modification resembling that of Fig. 2 except that the parts are so arranged that the cooling water first flows through the bearing 38 and then circulates through the roll, thus giving a somewhat greater cooling effect in so far as the bearing is concerned as is the case in the Fig. 2 construction. The pipe 39 is somewhat differently arranged at its right hand end than is the case with the constructions of Figs. 1 and 2, the ring 40 being welded to the pipe and provided with the packing 41. The right hand end of the pipe is provided with the ports 42. The bearing 38 is provided with a spiral passageway 43 and the inlet pipe 44 is connected to the left hand end of this passageway. The right hand end of the passageway 30 discharges into an annular recess 45 in the ring 46, such ring being provided with ports which register with the ports 47 through the wall of the spindle. To the left of the bearing member 38 is a ring 48 provided with suitable ports registering with the ports 49 through the wall of the spindle. Packing is provided on each side of the ring 48 as shown and also between the ring 46 and the end of the bearing member 38. Water supplied through the pipe 44 passes through the spiral groove 43 in the bearing member and discharges to the annular recess 45 at the end of the bearing member 38. Water supplied through the pipe 44 passes through the spiral groove 43 in the bearing member and discharges to the annular recess 45 in the ring 46. It then passes through the ports 47 into the space surrounding the end of the pipe 39. The water then flows to the left through the ports 42 and the pipe 8, and returns through the passageway 10 as heretofore described in connection with Fig. 1. The return flow of water passes out through the ports 49 and the ports in the ring 48 to the discharge pipe 50.

In this construction as in that of Fig. 1, a plate 51 is secured to the left hand end of the sleeve for keeping the parts inside the sleeve from endwise movement. The packing at each end of the sleeve is forced inward by means of the screws 52 which engage rings 53 in contact with the packing.

What we claim is:

1. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindles dividing it into two passageways communicating with each other in said body portion of the roll and terminating adjacent to but separated from each other in said sleeve, an inlet extending through the sleeve and communicating with one

passageway, an outlet extending through the sleeve and connected with the other passageway, and connections whereby liquid may be circulated through the passage in the bearing and through said passageways in the roll and spindle. 80

2. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindle dividing it into two passageways communicating with each other in said body portion of the roll and terminating adjacent to but separated from each other in said sleeve, an inlet extending through the sleeve and communicating with one passageway, an outlet extending through the sleeve and connected with the other passageway, connections for causing a flow of cooling liquid through the passage in the bearing, and other connections to said inlet and outlet for causing a cooling flow of liquid through said passageways in the roll and spindle. 90

3. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindle dividing it into two passageways communicating with each other in said body portion of the roll and terminating adjacent to but separated from each other in said sleeve, and connections whereby liquid is caused to pass through the passage in the bearing and said passageways. 105

4. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindle dividing it into two passageways communicating with each other in said body portion of the roll and terminating adjacent to but separated from each other in said sleeve, one of said separated ends being connected to one end of said passage in said bearing, and connections whereby a cooling flow of liquid is caused to pass in a circuit including said passage and said passageways. 115

5. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindle dividing it into two passageways communicating with each other in said body portion of the roll and terminating adjacent to but separated from each other in said sleeve, one of said separated ends being connected to one end of said passage in said bearing, and connections whereby a cooling flow of liquid is caused to pass 135

- first through the passage in the bearing and then through said passageways.
6. In combination in glass rolling apparatus including a pot or receptacle for carrying a bath of molten glass, a hollow sizing roll having a central body portion and bearing spindles at its ends, a supporting arm for one of said spindles including a sleeve surrounding the spindle and held against rotation, a bearing in the sleeve at the inner end thereof provided with a fluid cooling passage, means in the roll and its spindle
